SCOURING MACHINE

Eugene J. Ray, Beverly, Mass., assignor to United Shoe Machinery Corporation, Paterson, N. J., a corporation of New Jersey

Application July 6, 1935, Serial No. 30,189

8 Claims. (Cl. 51—81)

This invention relates to machines having a plurality of tools in which it is necessary to bring the tools in turn to a common operating position. It is illustrated as embodied in a machine 5 for scouring the heels of shoes.

The heel scouring operation is performed in a plurality (generally two) of steps, on scouring wheels of progressively increasing fineness of grade. When the shoe comes to the machine its heel, which has been roughly trimmed to shape, is first treated on a coarse scouring wheel, and later on a fine scouring wheel. The most common way of dealing with the problem is to mount such wheels side by side on the same shaft, which 10 has the disadvantage that the operator is obliged to change his position on the floor as he shifts from one tool to the other. This is time wasting and wearisome. It has been suggested that this procedure can be improved by mounting all 15 the tools so that they can be shifted one after the other to a common operating position, and it is with this type of machine that the present invention is concerned.

An important problem in the use of all machines which remove material from a work piece 20 is the disposal of the material removed. In the case of scouring and trimming machines, such material is removed by a suction pipe in cooperation with a dust hood surrounding the tool. It 25 is a principal object of the present invention to improve the waste material collecting and removing apparatus of such machines, while preserving the advantages of the common operative position of the tools.

Accordingly, I have provided a tool carrier 30 having a plurality of continuously driven tools mounted thereon and arranged to be moved into a common operating position by the operator, with a dust hood for each tool arranged to cooperate with a common suction apparatus at the common operative position, and so constructed that the hoods of the tools not in the operative position guard their tools from contact with a work piece being treated by the tool in the operative position. Thus I avoid loss of time in speeding up a tool newly brought to the operative position, and avoid damage to the work from a continuously driven though inoperative tool in the neighborhood of the operating tool.

In accordance with another feature of the invention I have provided a non-repeating mechanism for the machine. The shift of the tools is conveniently treadle actuated, and is very rapid so that an operator who is a little slow in releasing 55 the treadle would fail in his purpose of mov-

ing to the operative position the tool next succeeding the one he had been using, if he had not such a safeguard against overthrowing the tools. Preferably, the tool carrier is normally latched to hold one of the tools at the operative position and is positively driven, when unlatched, by a clutch, which, as well as the latch, is controlled by the treadle, and which, with the latch, is released by the non-repeating mechanism, in proper timed relation to the tool that is approaching the operative position.

These and other features of the invention comprising certain combinations and arrangements of parts will be apparent from the following description of a preferred embodiment of the invention shown in the drawings, in which

Fig. 1 is a side elevation of the machine;

Fig. 2 is a front elevation of the machine;

Figs. 3, 4 and 5 are sectional elevations on the corresponding section lines shown in Fig. 2; and

Fig. 6 is a detail showing the treatment of a heel by a scouring wheel in the machine.

The machine frame 10 carries a horizontal cylindrical bearing 12 at its upper end, in which is rotatably mounted a hollow cylinder 14, which is normally motionless, its rotation occurring only when the operator trips it. The cylinder 14 carries inside it, near its ends, the ball bearings 16, 18, in which runs the main operating shaft 20, with its drive pulley 22 on one end.

The cylinder 14, at its end remote from the pulley 22, carries a large casing 24 in which are mounted shafts 26, 28 carrying the scouring wheels 30, 32, respectively. These are driven by pinions 34 meshing with a pinion 36 on the end of the shaft 20, all of which pinions are contained within the casing 24. The casing 24 carries on its rear face two oppositely outwardly projecting lugs 38, 40 which are arranged to fall, in alternation, on a shelf 42 mounted on a bell-crank lever 44 pivoted at 46 on the frame 10. The shelf 42 is cushioned by a spring-pressed member 43. A spring 47 holds the lever 44 against a stop 45 in the position shown in Fig. 1. The lever 44 carries a spring-pressed latch 48 resting on top of the lug 38 to hold it against rising from the shelf 42.

The other arm 50 of the lever 44 rests on an abutment 52 pivoted at 54 on a rod 56 sliding vertically in a block 58 on the frame 10. The rod 56 is held down by a spring 59.

The cylinder 14, at its end near the pulley 22, carries three studs 60, on which is loosely mounted a clutch plate 62, which is held toward the cylinder 14 by springs 64 (Fig. 2) under the

heads of the studs 60. When the plate 62 is forced to the right in Fig. 2, it comes into frictional contact with the rim of the pulley 22, which then tends to drive the cylinder 14, casing 24 and its carried parts, to interchange the scouring wheels 30, 32.

This movement is instituted by a treadle 66, which pulls down on a rod 68, causing a rock lever 70 to rise and push up the rod 56, whereupon the abutment 52 tips the lever 44 to release the lug 38. At the same time a roll 72 mounted on the arm 58 of the lever 44, runs up on a cam surface 74 on a yoke 76, pivoted at 78, 78 on the frame 16. The yoke 76 carries, beyond its pivots 15 78, two rolls 80 which press against the plate 62 when the cam surface 74 is pushed back, and thereby effect the frictional driving contact, mentioned above, with the pulley rim, causing the casing 24 and the scouring wheels to revolve.

20 The plate 62 carries two lugs 82, 84 so arranged that, prior to the execution of a 180° turn by the casing 24, one of them will strike a finger 85 on the pivoted abutment 52 which has been thrown into the path of movement of the lugs 25 82, 84 by the raising of the abutment 52 (see the dotted line showing in Fig. 5) and throw the abutment clockwise in Fig. 1, releasing the end of the arm 58 and enabling the spring 47 to pull the lever 44 to its Fig. 1 position, permitting 30 release of the clutch 22, 62 by means of the spring 64, when the lug 38 or 40 which next comes along will strike the shelf 42 and stop the casing 24 at the end of the 180° revolution, even though the operator has not released the treadle. 35 Thus the tool shifting operation of the machine cannot repeat.

When the treadle is released the rod 56 drops and the abutment 52 slips under the end of the arm 58 again, as in Fig. 1.

40 Carried by the casing 24 is an integral structure comprising a pair of dust hoods 86 and 87 which are associated with the scouring wheels 30 and 32 respectively. Each of the hoods 86 and 87 partially encloses the scouring wheel with 45 which it is associated, covering the major portion of the periphery and sides of the scouring wheel but having an opening at which the work piece may be presented to the scouring wheel. This opening serves also as a draft inlet to receive dust-laden air from the vicinity of the work. The construction of the hoods 86, 87 is 50 the same. Each has an end portion 88 in which is formed a discharge opening adapted to register with an inlet opening in the upper portion 55 89 of a stationary dust chute or conduit 90. The inlet opening of each hood is preferably continuous with the discharge opening of that hood, as shown in Fig. 2. The ends 88 terminate in an imaginary cylindrical surface which is coaxial 60 with the shaft 20 and with the axis of rotation of the cylinder 14, and the portion 89 of the conduit 90 is complementary to the ends 88. Only a minimum clearance is necessary, therefore, to enable the ends 88 to be brought into register 65 with the portion 89. The interiors of the dust hoods 86 and 87 are separated by a partition 91 which constitutes a continuation of the rear wall of each dust hood, so that there is no communication between the hoods.

70 The conduit 90 has a discharge end 92 which is adapted to be connected to a suction system. In addition to the inlet opening in the upper portion 89 which communicates with the respective dust hoods, the conduit 90 has a widely flared 75 hopper-like space 93 bounded by a rim 93* and

opening into the room, beneath the locality at which the scouring operation is performed upon a shoe 104. A partition 93½ divides the conduit 90 into two passageways 94 and 96 from a point adjacent to the discharge end 92 and leading respectively to the inlet opening in the portion 89 and to the flared opening 93. The size and shape of the opening 93 are such as to enable it to catch practically all of the dust which drops downwardly from the shoe 104, and also to provide space for manipulation of the shoe when in the position indicated in Fig. 6, that is, when the toe of the shoe is pointed downwardly and toward the left, as viewed in Fig. 1. In order to speed up the draft and thereby to avoid the accumulation of dust on the walls of the conduit, the wall of the conduit 90 is shaped to contract the hopper-like space 93 as the draft progresses from the rim 93* to the discharge opening 92. Such contraction assumes the form of a relatively narrow slot 100 which flares out to the rear into the passage 96.

As one or the other of the scouring wheels operates upon the shoe 104, the scouring wheel, which rotates in the direction indicated by the 25 arrows on Fig. 1, creates a strong peripheral draft. This draft entrains a considerable amount of the dust resulting from the scouring operation, and carries this dust into the opening 93* and into the inlet opening of the hood below 30 the wheel, the dust-laden air being thence drawn by suction through the conduit 90. The above-mentioned peripheral draft tends to carry a portion of entrained dust completely around the wheel, but the current of incoming air which enters the hood above the wheel strips off such dust and draws it down through the back of the hood and into the passageway 94.

As previously stated, the interiors of the hoods are separated from each other by the partition 91. 40 The hood associated with the scouring wheel which is not in use is therefore shut off from the suction system, and no draft is wasted. It will be noted, however, as shown in Fig. 1, that the two dust hoods are symmetrical with respect to 45 the axis of the shaft 20, and the exposed portion of the wheel which is not in use will therefore be directed away from the operator. The hood associated with the wheel which is not in use will therefore function as a guard for that wheel, preventing the forepart of a shoe which is being 50 scoured from being damaged by accidental contact with that wheel.

Having described my invention, what I claim as new and desire to secure by Letters Patent of 55 the United States is:

1. In a machine of the class described, a tool holder, a plurality of continuously actuated rotary abrasive tools mounted on parallel axes on said holder, said holder being constructed and arranged to move the said abrasive tools in succession to a common operative position, and a dust hood for each of said abrasive tools mounted on the tool holder, said hoods being open on the operative sides of the abrasive tools and closed on the opposite sides of the tools, the open side of that hood which is in operative position and the closed side of the hood next adjacent thereto being located on the same side of the plane defined by the axes of the tools in the two last-mentioned 60 hoods, whereby that dust hood associated with said next adjacent tool serves as a guard for that tool and precludes contact between it and a work piece being treated by the tool that is in operative position.

2. In a machine of the class described, a revolving tool holder, a plurality of rotating abrasive tools mounted on parallel shafts on said holder, said holder being constructed and arranged to revolve the said abrasive tools in succession to a common operative position, a dust hood for each of said abrasive tools mounted on the revolving tool holder, each of said hoods being open on the leading side of its abrasive tool and closed on the following side of the tool as the tools are revolved by the holder, the closed portion of each hood being arranged to envelop its associated tool over substantially that entire portion thereof which lies to one side of a plane passing through the axis of rotation of the tool and through the axis of rotation of the next adjacent tool, whereby that dust hood associated with a tool not in operative position serves as a guard for that tool and precludes contact between it and a work piece being treated by the tool that is in operative position, means actuatable by the operator to cause the tool holder to revolve the abrasive tools, and automatic means for stopping the revolution when the tool next to that which was in the said operative position before said actuation has come to the operative position. 5
3. In a machine of the class described, a revolving tool holder, a plurality of continuously actuatable abrasive tools mounted on said holder, said holder being constructed and arranged to revolve the said abrasive tools in succession to a common operative position, a dust hood for each of said abrasive tools mounted on the revolving tool holder, said hoods being open on the operative sides of the abrasive tools and closed on the opposite sides of the tools and having their open sides facing the same way around the holder, whereby that dust hood associated with a tool not in operative position serves as a guard for that tool and precludes contact between it and a work piece being treated by the tool that is in operative position, each of said dust hoods having also a discharge opening, and a suction pipe having a receiving opening arranged to register with the said discharge openings in turn as the tools associated with the said openings come, in turn, to the said operative position. 10
4. In a machine of the class described, a revolving tool holder, a plurality of tools angularly spaced around said holder, said holder being constructed and arranged to revolve said tools, in turn, to a common operative position, a pulley for driving said tools, a friction device between the pulley and the tool holder for revolving the tool holder, said friction device being actuatable by the operator, automatic means for putting the friction device out of operation when the tool holder has revolved through the angle existing between one tool and the next, and means for holding the tool holder with one of the tools in the operative position, said holding means being released in connection with the actuation of the friction device by the operator. 15
5. In a machine of the class described, a revolving tool holder, a plurality of tools spaced circularly on said holder, a set of stop members on the holder arranged in like relation to the tools respectively, a latch on the machine frame arranged to cooperate with all the stop members in turn to hold the tool holder against revolving in either direction, and to hold the tools in turn in a common operative position, a clutch located between the tool holder and the main drive of the machine for revolving the tool holder when the clutch is engaged, manually-operated means for tripping the latch and the clutch, and a second set of stop members arranged to free the latch and the clutch before the revolving tool holder has advanced to the common operative position that tool which next follows the tool which was in the operative position when the latch and clutch were tripped, whereby repetition of the revolving of the tool holder due to a single actuation by the operator is prevented. 20
6. In a heel scouring machine, a plurality of scouring wheels, a casing carrying said wheels and arranged to revolve them in turn about an axis to a common operative station, said casing comprising dust hoods covering the inoperative sides of the wheels and having discharge openings lying substantially in a cylindrical surface around the said axis of revolution, and a suction dust remover having a widely flared end comprising two channels, one of which has an end registering with the said openings of the dust hoods, respectively, when the wheels appertaining to the hoods are in operative position, and the other of which channels opens out into a flared hopper the bottom of which communicates with the suction dust remover through a tapering throat, and through a narrow slot communicating with the throat, said hopper lying beneath a shoe being applied to a wheel in operative position. 25
7. A suction draft device comprising a plurality of draft hoods, supporting means for said hoods constructed and arranged to enable said hoods to be brought successively into a common operating position, and a conduit having a discharge end adapted for connection to a suction draft system and having a receiving opening adapted to communicate successively with each of said draft hoods when the hoods are brought one by one into said operative position, said conduit having also a receiving orifice which is open to the atmosphere and which cooperates with the hood occupying the operative position in directing a suction draft. 30
8. An abrading machine comprising a plurality of abrading tools, a draft hood associated with each of said tools, supporting means constructed and arranged to enable each of said tools and its associated hood to be brought successively into a common operating position, and a conduit having a discharge end adapted for connection to a suction draft system and having a receiving opening adapted to communicate successively with each of said draft hoods when the hoods are brought one by one into said operative position, said conduit having also a draft receiving orifice positioned below the abrading tool which occupies the operative position, which orifice cooperates with the hood associated with that tool in removing dust-laden air from the vicinity of the tool. 35

EUGENE J. RAY.
